UNITED STATES PATENT OFFICE.

FRANCIS N. VANIER, OF AMESBURY, MASSACHUSETTS.

TWO-SEATED CARRIAGE.

SPECIFICATION forming part of Letters Patent No. 463,179, dated November 17, 1891.

Application filed June 6, 1891. Serial No. 395,321. (No model.)

To all whom it may concern:

Be it known that I, FRANCIS N. VANIER, a subject of the Queen of Great Britain, residing in Amesbury, in the county of Essex and State of Massachusetts, have invented a new and useful Improvement in Two-Seated Carriages, of which the following is a specification.

This invention relates to two-seated carriages or wagons which are provided with doors on the sides for admission to and egress from the rear seat; and it consists in the means below described, whereby the opening of one of the side doors will cause the front seat on that side to swing down, the lazy-back at the same time folding against it, providing ample room on that side for the occupant of the rear seat to pass out between the rear seat, which remains stationary, and the front seat, which is swung down into a substantially vertical position.

In the accompanying drawings, in which similar letters of reference indicate like parts, Figure 1 is a central longitudinal vertical section with the seats in position for use, the position of the front seat when swung down being indicated by broken lines. Fig. 2 is a plan view with one of the front seats swung down.

30 A A' A² A³ represent, respectively, the floor, sides, tail-gate, and dash-board of the carriage.

B B are the doors, and C is the rear seat, all constructed substantially as usual.

35 D is a horizontal cross-piece supported by the frame D' and situated beneath the front seats well forward of their centers.

E E are the two front seats supported by the cross-piece D and each hinged thereto at e. Each of these front seats E is connected with the door B on the same side by means of a connecting-rod H, the ends of the rod being loosely attached to the door and seat by means of eyes h h or equivalent mechanical devices. The rods are connected to the under side of the seat at a point toward its rear edge and to the inner side of the door near its lower edge, so that said rod extends diagonally from the seat to the door.

50 As will readily be seen, opening the door pulls down the seat, which swings on the hinges e into the vertical position shown by broken lines in Fig. 1 and by full lines in Fig.

2. This leaves a wide passage out between the seats on that side of the carriage. The 55 lazy-back I is disposed of at the same time by the following means: The lazy-back is supported by the standards I', which extend up from the horizontal rod J, supported in bearings K, extending from the seat E. This 60 rod is bent at its inner portion J' at right angles, and its hooked end J'' holds loosely one end of the rod L, whose other end is caught in an eye N on the under side of the cross-bar D. Thus when the seat is pulled 65 down by the opening of the door the rod L acts on the portion J' of the rod J and folds the lazy-back against the seat, as seen in Fig. 2 and broken lines, Fig. 1.

Having thus fully described my invention, 70 what I claim, and desire to secure by Letters Patent, is—

1. In a two-seated carriage provided with doors at the sides between the seats, the combination of the door B, the front seat E, 75 hinged at its under side to a cross-bar D, and the connecting-rod H, secured at its opposite ends to said door and seat, whereby the opening of the door causes the said seat to swing down into a substantially-vertical 80 position, substantially as set forth.

2. In a two-seated carriage provided with doors at the sides between the seats, the combination of a front seat pivoted on its under side to the carriage, a swinging door in the 85 side of the carriage, and a connecting mechanism whereby the opening of the door swings the said seat down into a substantially vertical position and the closing of the door swings it into its normal horizontal position, 90 substantially as described.

3. The combination, with the seat E, hinged to the carriage-frame and adapted to be lowered and raised by the opening and closing of the door, of the rod J, supporting the lazy-back, said rod being supported in bearings K and bent, as described, at J', and the rod or link L, loosely connected with the end of the portion J' of said rod J and the frame of the carriage, whereby when the seat is lowered the lazy-back will fold against it, substantially as set forth.

FRANCIS N. VANIER.
